APPARATUS FOR MOUNTING FUR UPON A
CARRIER SHEET

Robert H. Plass, Upper Montclair, N. J.

Application August 8, 1939, Serial No. 288,930

4 Claims. (Cl. 149—24)

This invention relates to apparatus for gluing fur pieces to flexible sheet material, such, e. g., as paper, and the same has reference, more particularly, to novel apparatus adapted for use in the operation of assembling fur pieces, which may comprise fur scrap or whole skins, in substantially edge to edge relation to form a desired substantially continuous area of pieced fur and thereupon apply and affix the so assembled pieces of fur or skins to a flexible carrier or backing sheet by an applied adhesive; this application being a continuation in part of my prior application for United States Letters Patent Ser. No. 244,157, filed December 6, 1938, now Patent No. 2,175,309.

Fur scrap, comprising trimmings and cuttings from animal pelts, constitutes a waste product of garment manufacturing and like industries, and provides a source of raw material from which hat fur may be obtained. Owing, however, to the small size and irregular shapes of such fur scrap, the individual pieces thereof cannot be satisfactorily or profitably handled in application to dehairing machines, and consequently, the hat fur industry, in order to dehair such fur scrap, must first assemble a plurality of the fur scrap pieces edge to edge in glued attachment to and upon a flexible carrier or backing sheet, such, e. g., as paper, to thereby form a flexible layer thereof of substantial area suitable for efficient manipulation and application to dehairing machinery. Heretofore the operations of assembling and gluing the pieces of scrap fur to a carrier or backing sheet has been wholly performed by hand operations, which are slow, tedious, laborious and comparatively expensive. Furthermore, such hand operations are not entirely satisfactory in result for the reason that the operator must coat with an adhesive, such as glue, the skin side of such individual piece of scrap fur, and then apply the coated skin side thereof to the sheet material upon which the same is to be assembled and mounted. In so doing, the hair sides of the pieces must be turned upward or outward, and since the hair tends to overhang the edges of the skin, these edges are concealed from the view of the operator, thus rendering it almost impossible to closely assemble and mount the pieces without either overlapping or leaving intervening gaps, and consequently it is difficult to attain that smooth and close edge to edge matching or piecing which is desired and which disposes the scrap to the best advantages for the efficient carrying out of subsequent dehairing operations.

Having the above mentioned and other objections to hand assembling and pasting of fur scrap, or whole skins or pelts, as the case may be, to a carrier or backing sheet in view, it is an object of this invention to provide a novel apparatus whereby the assembling of fur scrap pieces or even whole skins by the operator in desired closely disposed edge to edge relation may be more easily and rapidly carried on, and whereby the pieces are automatically brought into engagement with and secured to a glue coated carrier or backing sheet.

Other objects of this invention, not at this time more particularly enumerated, will be understood from the following detailed description of the same.

An illustrative embodiment of this invention is shown in the accompanying drawings, in which:

Fig. 1 is a side elevation, Fig. 2 is a top plan, and Fig. 3 is a central longitudinal vertical section of the novel apparatus, according to this invention, for mounting pieced fur upon a carrier sheet.

Fig. 4 is a fragmentary top plan view, drawn on an enlarged scale, and showing the manner in which the scrap fur pieces are assembled and held subject to the application thereto of a glue coated carrier or backing sheet; and Fig. 5 is a longitudinal vertical section, taken on line 5—5 in Fig. 4.

Similar characters of reference are employed in the above described views, to indicate corresponding parts.

A novel apparatus suitable for the practice of the method of fur piecing and mounting according to this invention, in the illustrated embodiment thereof, comprises a supporting frame provided by laterally spaced slide members 10, supported at their ends by suitable standards or leg members 11. Said side members 10 are secured in laterally spaced relation by transverse tie bars or rods 12. Freely rotatable on a shaft 13, mounted upon and between said side members 10, is a drum 14. Said drum 14 is located adjacent to one end of the apparatus. Spaced away from said drum 14, at a suitable distance therefrom, is an upper idler roller 15 and a lower idler roller 16. Said rollers 15 and 16 are supported by shafts 17 mounted upon and between said side members 10. Running over said drum 14 and the upper and lower idler rollers 15 and 16 is an endless belt or apron 18, preferably of such character as to provide a roughened surface adapted to offer frictional resistance to the pieces of fur applied thereto sufficient to resist shift-

ing displacement of the applied fur, e. g., a wire mesh material may be satisfactorily employed for such belt. The upper course of this belt runs horizontally between said upper idler roller 15 and said drum 14 adjacent to the top of the apparatus.

Supported across the top of the frame of the apparatus, with its forward open end contiguous to the receiving end of the forwardly running upper course of said belt or apron 18 is a hopper or bin 19 in which may be deposited a supply of fur scrap desired to be pieced together and mounted upon a carrier or backing sheet.

Cooperative with that portion of the belt or apron 18 which runs over and around the drum 14 is an endless presser belt or apron 20 which substantially corresponds in width to the width of the belt or apron 18. Said presser belt or apron 20 is preferably made of rubberized canvas or similar material. Said presser belt or apron 20 is supported by idler rollers 21, 22 and 23 and by a driven roller 24. Said idler rollers are mounted on shafts 25 supported by and between the frame side members 10, and said driven roller 24 is fixed on a driven shaft 26 mounted upon and between the frame side members 10. The idler roller 21 is disposed somewhat in advance of the drum 14 above the upper course of said belt or apron 18. From said idler roller 21 the presser belt or apron 20 runs forwardly in contact with the wire screen belt or apron and extends with the latter around the drum 14, and thence rearwardly contiguous to the lower course of the belt or apron 18 to and around the driven roller 24, thence extending in a return course forwardly to and around the idler roller 23, thence upwardly to and around the idler roller 22 from which it returns to said idler roller 21.

The means for driving the presser belt or apron 20 and associated belt or apron 18 comprises a main drive shaft 27 mounted in bearings 28 at one end of the supporting frame, said shaft 27 being suitably driven from a source of power, as e. g., by belt actuated fast and loose drive pulleys 29. Affixed on said drive shaft 27 is a drive sprocket 30 which actuates a drive chain 31 that engages a driven sprocket 32 affixed to said driven shaft 26. By this power transmission means the driven roller 24 is rotated in a clockwise direction, thus driving the pressure belt or apron 20, and by its frictional engagement with the belt or apron 18, directly or through interposed material, causing the latter and its supporting drum 14 to run in an anti-clockwise direction.

Means are provided for drawing off sheet material from a supply roll and thereupon coating a face of the same with an adhesive, to thus furnish a flexible carrier or backing sheet upon which the pieced fur scrap is to be mounted. This means comprises a pair of bearing brackets 33 to support, at the forward end of the apparatus, a transverse spindle 34 upon which is rotatably mounted a roll of sheet material 35, such, e. g., as paper. Mounted between the side members 10 of the frame of the apparatus, in a location above the drum 14, is means for applying liquid glue or like cementitious substance to a face of the sheet material 35 preparatory to applying the pieced fur scrap thereto, the same comprising a glue reservoir 36 in which is revolved a transverse coating roll 37, the shaft 38 of which is provided with a pulley 39 over which runs a drive belt 40 from a drive pulley 41 operated by said main shaft 27. Mounted upon and

across the side members 10 of the apparatus frame is a lower guide roller 42 and an upper guide roller 43, the latter running contiguous to said coating roll 37. The sheet material passes from the supply roll thereof to and around the lower guide roller 42 and thence between the upper guide roller 43 and said coating roll 37, so as to pass a face of the sheet material in contact with the latter, and thence downwardly over the pressure belt or apron 20, where the latter passes over the idler roller 21, whereby the leading end portion of the coated sheet material 35 may pass between said pressure belt or apron 20 and the belt 18, so as to be gripped and moved therebetween together with the pieced fur to be applied to the glue coated face of said sheet material, as will be subsequently more fully explained.

Suitably supported between the side members 10 of the apparatus frame is a table or plate 44 which underlies the belt or apron 18 along the extent of the latter moving between the upper idler roller 15 and the pressure belt or apron supporting idler roller 21.

Mounted beneath and in opposition to said pressure belt or apron supporting idler roller 21, is a spring pressed pressure roller 46 to yieldably urge the forwardly moving courses of said belt or apron 18 and pressure belt or apron 20 together so as to operatively grip the sheet material 35 and pieced fur scrap interposed therebetween.

In the use of the apparatus, the fur scrap to be pieced is deposited within the hopper or bin 19, and the operator, standing beside the apparatus, takes therefrom the pieces of fur scrap 47, or whole skins as the case may be, and lays them upon the belt or apron 18 while the latter moves slowly forward toward the drum 14. The operator starting at the far margin of said belt or apron, applies the pieces of fur scrap 47, fur side down, across the same, being careful to bring the margins of said pieces as closely contiguous as possible, thus forming a layer of closely pieced fur across the width and along the length of said belt or apron 18, as the latter moves forward. The frictional effect exercised by the roughened surface of the belt or apron 18 upon the hair side of the fur pieces or skins causes the latter to be held thereon against displacement from the pieced assembled relation in which the operator has disposed the same. In the meantime, the glue coated carrier or backing material 35 is moved to pass between the presser belt or apron 20 and said belt or apron 18, and in such manner that its glue coated face is opposed to the wire screen belt or apron. As the belt or apron 18 carries the assembled pieced fur scrap forwardly, the upwardly facing skin sides of the latter are opposed to the glue coated face of the carrier or backing material 35, as it passes therewith between the presser belt or apron 20 and the belt or apron 18, and thence around the drum 14, so that said skin sides of the assembled fur scrap are pressed against and adhered to the carrier or backing material 35 during the travel thereof around the drum 14.

In the operation of matching and piecing the fur scrap while assembling the same on the belt or apron 18, there is likelihood that portions of the fur scrap pieces will overhang the near margin of the belt or apron 18 toward which the operator works when piecing the fur scrap in assembled relation thereon. In view of this, provision is made for shearing or trimming off such

overhanging fur portions, and to this end a rotary knife 48 is mounted adjacent to and for cooperation with an end of the drum 14 in such manner as to shear away such overhanging fur portions. The side member 10 of the apparatus frame, adjacent to which said rotary knife 48 is mounted, is provided with an open way 49 contiguous to the near margin of the belt 18, so that the overhanging fur portions may unimpededly move therethrough toward the knife 48. Said way 49 terminates in an enlarged lateral discharge opening 50 near the knife location, so that the fur portions sheared away by the knife 48 may fall outwardly therethrough and exteriorly of the apparatus. Said rotary knife 48 is mounted on a driven shaft 51 journaled in and between the frame side members 10, and an exterior end of said shaft 51 is provided with a pulley 52 over which runs a drive belt 53 driven by a drive pulley 54 mounted on the main shaft 27. In order to maintain the courses of the presser belt or apron 20 and the belt 18 as they pass away from the drum 14 firmly urged together, and in maintained gripping relation to the interposed carrier or backing material 35 and pieced fur scrap 41 applied to the latter, said courses are caused to move over a convexly curved supporting member or block 55. In this manner, the carrier or backing material and applied fur are held together for a sufficient length of time to assure setting of the glue by which the same are adhered together.

As the carrier or backing material 35 with the assembled fur scrap adhered thereto emerges from between the presser belt or apron 20 and the belt or apron 18, the same is extended rearwardly to a take up roll 56, the spindle 57 of which is removably journaled in bearing brackets 58 connected with the rear end of the apparatus frame. Means for rotating said roll 56 to wind up the backed fur thereon, comprises a belt drive pulley 59 affixed to the driven shaft 26 and a belt driven pulley 60 affixed to the roll spindle 57, over which pulleys runs the transmission belt 61, the same being crossed to apply proper take up rotation to the take up roll 56.

From the above description it will be obvious that a novel and efficient means for assembling fur on a carrier sheet is provided by this invention.

It will be understood that many changes could be made in the construction of the described apparatus, that many apparently widely different variations of this invention could be made without departing from the scope thereof as defined by the following claims. It is therefore intended that all matter contained in the above description

or shown in the accompanying drawings shall be interpreted as illustrative and not in a limiting sense.

I claim:

1. In apparatus of the kind described, a conveyer belt and a presser apron supported and driven so that portions of the courses thereof run in opposed contiguous relation, means to supply a run of carrier sheet material for engagement between opposed courses of said belt and apron, means to apply an adhesive coating to that face of said carrier sheet material which is to run in opposition to said conveyer belt when said carrier sheet material passes between the latter and said presser apron, and said conveyer belt having an exposed receiving course operative to carry fur pieces applied thereto in pieced together assembled relation into engagement with the adhesive coated face of the carrier sheet material while passing with the latter between the opposed sources of said belt and apron.

2. In apparatus as defined in claim 1, a shearing means operative to trim away portions of fur pieces applied to the carrier sheet material which project beyond a side margin of the latter.

3. In apparatus of the kind described, a rotatable drum, idler rollers spaced relative to said drum, an endless conveyer belt supported by said drum and rollers so as to provide an exposed receiving course thereof leading to said drum, and an endless presser apron, a series of carrying rollers to support said apron, one of which is located in advance of said drum so as to lead a portion of said apron to run in superposed relation to said conveyer belt and to pass therewith around said drum, means to impart operative motion to said apron and belt, means to supply a run of carrier sheet material for engagement between the opposed courses of said belt and apron, means to apply an adhesive coating to that face of said carrier sheet material which is to run in opposition to said belt when said carrier sheet material passes between the latter and said apron, said exposed receiving course of said belt being operative to carry fur pieces applied thereto in pieced together assembled relation into engagement with the adhesive coated face of the carrier sheet material while passing with the latter between the opposed courses of said belt and apron.

4. Apparatus as defined in claim 3, including means cooperative with the opposed sections of the return courses of said belt and apron adapted to tauten the same into firm holding contiguous relation to the intervening fur bearing portions of said carrier sheet material.

ROBERT H. PLASS.
